UNITED STATES PATENT OFFICE.

ALBERT PRYIBIL, 2d, OF NEW YORK, N. Y.

IDENTIFICATION NAME PLATE FOR UMBRELLAS.

Application filed January 19, 1921, Serial No. 438,316. Renewed April 13, 1925.

To all whom it may concern:

Be it known that I, ALBERT PRYIBIL, 2d, a citizen of the United States, residing at New York, in the county of New York and 5 State of New York, have invented certain new and useful Improvements in Identification Name Plates for Umbrellas, of which the following is a specification.

This invention relates to means for associating with an umbrella, parasol or the like, a holder for an address or identification card, in such a manner and in such a position that the card will be substantially hidden from view in ordinary conditions of 15 use.

A further object is to provide for the equipment of an umbrella or the like with an identification or address card by means attachable to or forming a part of an element of the umbrella which is concealed when the umbrella is closed and which is exposed to view from beneath the umbrella when the latter is opened.

Other objects and aims of the invention, 25 more or less broad than those stated above, together with the advantages inherent, will be in part obvious and in part specifically referred to in the course of the following 30 description of the elements, combinations, arrangements of parts, and applications of principles constituting the invention; and the scope of protection contemplated will appear from the claims.

In the accompanying drawings, which 35 are to be taken as part of this specification, and in which I have shown merely a preferred form of embodiment of invention, Figure 1 is a central vertical section of a part of an open umbrella showing my identification card holder combined with a stay or brace of the umbrella: Figure 2 illustrates in perspective a separable support for an identification card, which support is adapted to be frictionally held by and within 40 a stay or brace of familiar construction; Figure 3 is a sectional view through a channeled brace or stay, showing in end elevation an identification card holder detachably and releasably held in position on the stay; Figure 4 is a bottom plan view of the subject-matter of Figure 3; Figure 5 is a view 45 similar to Figure 3 illustrating a modified means for holding an identification card support in position on a stay; and Figure 50 55 6 is a side elevation illustrating the subject-matter of Figure 5.

Referring to the numerals on the drawings, and first to Figure 1, there is indicated at 8 the central rod of an umbrella, having a cover 9, rib 10, stay or brace 11, all of these parts being connected together in the usual way, and the brace 11 being pivoted at one end to the rib 10 and at the other end to a slide 12, which moves up and down on the central rod 8.

In Figure 2 I have shown a detachable card holder made up from sheet metal and comprising a slideway 19 with a card 16 therein and an integral rib or fin 20 extending along the bottom of the holder. This fin will be of such width that it may be forced into the channel of the brace or stay, where it will be held by friction, assuming that the interengaging parts are of proper relative size, &c. In this figure, also, I 75 show the slideway for the card closed at both ends by end-pieces 18. The ends of the card are inserted under these stops and the card flattened down into proper position. And for the ready removal of the 80 card I may provide a cut-out 28 in one of the side walls of the slideway, through which the edge of the card is accessible for lifting it up. This arrangement may also be used with the card holders shown in the 85 other figures.

In Figures 5 and 6 I show a construction in which reliance is not placed on the frictional hold, but clamp members 21 surround and bear against both the holder and the 90 stay, the clamp members being held together by means of screw and nut connection 22.

In Figures 3 and 4 I show still another arrangement, whereby the card holder may be held in position on the stay and readily 95 removed therefrom when desired. In this embodiment the card holder, indicated in a general way at 19 and including the sort of slideway heretofore described, carries below it a clamp 24, which is pivoted at 25, and urged by means of a spring 26, to the Figure 3 position. This form of the device is useful in connection with the stays of different sizes, as will be obvious; and in order to prevent rotation of the device about the 100 stay, I may provide a lug 27 on the bottom of the card holder which enters the channel of the stay, in somewhat the same way as the fin 20 shown in Figure 2.

Inasmuch as the stays 11 are ordinarily 110 positioned so that the channels thereof open downwardly when the umbrella is open and

held over the person, it will be obvious that when a card holder such as I have described is in position on the stay, the card will be visible and readable to the person holding 5 the umbrella. And obviously it will be normally invisible to other persons when the umbrella is open and will at all times be hidden from view when the umbrella is closed. The arrangement shows distinct ad- 10 vantages over the methods heretofore employed of fastening a name plate or the like to the handle of an umbrella. This was difficult because the different shapes of handles are innumerable and a standard 15 name plate is practically impossible. Furthermore, many persons object on aesthetic grounds to having their names and addresses published in such a way. The rib of an umbrella would not serve so well as a sup- 20 port for the card holder because in opening the umbrella it is bowed. And the central rod will not serve, because the slide 12 moves up and down on it. And the slide itself is not large enough to carry a card.

25 Inasmuch as many changes could be made in the above construction, and many apparent widely different embodiments of my invention could be made without departing from the scope thereof, it is intended that 30 all matter contained in the above description or shown in the accompanying drawings shall be interpreted as illustrative and not in a limiting sense.

It is also to be understood that the 35 language used in the following claims is intended to cover all the generic and specific features of the invention herein described and all statements of the scope of the inven-

tion which, as a matter of language, might be said to fall therebetween.

40 I claim:

1. The combination with a channel brace or stay of an umbrella, of an elongated card holder comprising a slideway for a card and a fin or rib on said holder for engagement 45 within the channel of the brace.

2. The combination with a channel brace or stay of an umbrella, of an elongated card holder comprising a slideway for a card and a fin or rib on said holder for engagement within the channel of the brace, and 50 means for clamping the holder in position on the brace.

3. The combination with a channel brace or stay of an umbrella, of an elongated card holder comprising a slideway for a card and a fin or rib for engagement within the channel of the brace, and spring-pressed 55 means for releasably securing the holder in position on the brace.

4. The combination with a channel brace or stay of an umbrella, of an elongated card holder comprising a slideway for a card and a fin or rib on said holder for engagement 60 within the channel of the brace, and means for releasably securing the holder in position on the brace.

5. The combination with a channel brace or stay of an umbrella, of an elongated card holder comprising a slideway for a card and 65 provided with an integral fin or rib on its rear face for insertion within the channel of the brace to hold the card holder in position on the brace.

70 In testimony whereof I affix my signature.

ALBERT PRYIBIL, 2ND.
